CONTAINER CLOSURE

Roman B. Bukolt, Stevens Point, Wis.

Application August 1, 1934, Serial No. 737,987

11 Claims. (Cl. 220—55)

The invention relates to container closures of the general type disclosed in my pending U. S. application Serial No. 719,961, filed April 10, 1934, in which a closure is held sealed through the 5 instrumentality of a lever-and-toggle-action snap disk.

It is the object of the invention to provide a rather inexpensive and highly efficient structure which may be advantageously manufactured for 10 relatively large containers such as kegs, drums, barrels, etc., novel provision being made whereby the snap disk may be removed when it is snapped to released position, allowing access to be had to the interior of the container for removing its contents.

The snap disk is provided with a central opening through which a tool must be inserted in order to snap said disk to released position, and a further object is to provide a unique seal for this 20 opening so that the seal must be broken before the container is opened. It is thus insured that if the seal be intact, the contents have not been tampered with.

With the foregoing in view, the invention resides in the novel subject matter hereinafter described and claimed, description being accomplished by reference to the accompanying drawings.

Fig. 1 is a top plan view partly broken away 30 showing a closure for a wooden keg, barrel or the like.

Fig. 2 is a vertical sectional view on line 2—2 of Fig. 1.

Fig. 3 is a fragmentary top plan view showing 35 one form of closure for use on a metal container.

Fig. 4 is a sectional view on line 4—4 of Fig. 3. Figs. 5 and 6 are views similar to Fig. 4 but illustrating different forms of construction.

In Figs. 1 and 2, the head 7 of a barrel or 40 keg or any other wall of some other type of wooden container, is formed with an opening 8 having an annular outwardly facing seat 9 for a sealing ring 10. The outer end 11 of the opening 8 is somewhat enlarged to provide space to receive 45 the peripheral portion of the lever-and-toggle-action snap disk 12. A flat metal rim 13 is secured by rivets or the like 14 upon the wall 7, the inner ends of said rivets or the like being countersunk and covered with a suitable compound 50 15 to prevent them from contacting with the container contents. The inner edge of the rim 13 is provided with circumferentially spaced lugs 16 which overlie the peripheral edge of the snap disk 12, and said snap disk edge is provided

with fulcrum lugs 17 which normally abut the inner sides of the rim lugs 16. By turning the snap disk 12 when it is sprung outwardly to released position however, the fulcrum lugs 17 may pass between the rim lugs 16 allowing easy removal 5 of the snap disk. The closure 18 which occupies the opening 8 and rests upon the sealing ring 10 may then also be removed to give access to the interior of the container.

The closure 18 is preferably of wood and it is 10 provided with a pivoting bead 19 which contacts with the disk 12 near the peripheral edge of the latter. At its center, the disk closure is provided with a depression 20 having a metal wear-plate 21 on its bottom. This depression and wear-plate are directly below a central opening 22 15 in the snap disk 12. A suitable tool must be inserted through opening 22 to pry the disk 12 outwardly to released position, and the wear-plate 21 prevents the tool from injuring the closure 19. 20

A thin metallic seal 23 is provided for the opening 22, said seal being cupped as shown and being flanged at 24 and 25 to abut opposite sides of the snap disk 12. The seal cannot be removed and the closure opened without detection and 25 hence constitutes an effective means to prevent undetected tampering with the container contents.

When the container is to be sealed, the closure 18 and sealing ring 10 are placed in the opening 30 8 as shown in Fig. 2, the snap disk 12 which then occupies an outwardly sprung or snapped position, is inserted by guiding its lugs 17 between the rim lugs 16, and said disk is then turned so that said lugs 17 underlie said lugs 16. A suitable 35 stop 26 may be provided to limit the extent of turning of the disk 12 both when applying it and when later removing it. The disk having been properly positioned, it is snapped inwardly to the position shown in Fig. 2, so that it fulcrums upon its lugs 17 and exerts a strong inward force against the bead 19, compressing the sealing ring 10 and tightly sealing the container.

To open the container, the seal 23 is cut and removed and a suitable prying tool is inserted 45 through the opening 22 so that said tool may act upon the disk 12 and react upon the wear-plate 21 to effect outward snapping of said disk to released position. When in this position, the disk 12 may be readily turned to the necessary extent 50 and removed, whereupon the cover 18 may be removed. This cover may be provided with a plate or the like 27 projecting partially over the depression 20 to facilitate removal of said cover.

The stop 26 may well be in the form of an L- 55

shaped pin inset in the wall 7 and held in place by the rim 13.

In the forms of construction shown in Figs. 3, 4, 5, and 6, I provide metallic rim means 28 around the container opening to form an annular channel whose open side is toward the center of said opening, said channel having an outer side flange 29 and a wider inner side flange 30. A sealing ring 31 rests upon the flange 30 which constitutes an outwardly facing seat for said sealing ring, a closure 32 of metal rests upon said sealing ring, and a snap disk 33 is provided to inwardly force said closure and tightly compress the sealing ring.

15 The outer side flange 29 of the channeled rim 28 is formed with circumferentially spaced notches 34 and the peripheral edge of the snap disk 33 is provided with similarly spaced lugs 35. When the disk 33 is in outwardly snapped released 20 position, it may be turned so that its lugs 35 may pass through the notches 34, allowing the disk to be easily inserted or removed, and a suitable stop 36 may be provided to limit the extent of turning of said disk.

25 After positioning the sealing ring 31 and the cover 32, and inserting and turning the snap disk 33 with the latter in outwardly sprung released position, said snap disk is snapped inwardly to the position shown in full lines in Figs. 30 4, 5, and 6. As the disk moves to this position, it fulcrums upon its lugs 35 and it presses inwardly upon the pivoting bead 37 of the closure 32 so that the sealing ring 31 is compressed and the closure tightly sealed.

35 The disk 33 is provided with a central seal 38 which must be broken before it can be sprung outwardly to released position. When this seal is broken however, and a tool inserted to outwardly snap the disk 33, this disk may be turned sufficiently to allow it to be disengaged from the rim 28. Then, the cover 32 may be easily removed. This cover may be provided with a button or the like 39 to facilitate removal.

45 While the structures shown in Figs. 3 to 6 possess the features in common so far described, their structural details are somewhat different as will now be explained.

In the structure shown in Figs. 3 and 4, the flanges 29 and 30 are integral with a side wall 40 for the channeled rim 28, said wall 40 being welded at 41 to the container head or wall 42.

55 In Fig. 5, the side wall 43 of the channeled rim 28 is integral with the flange 30 and is provided with an outwardly projecting flange 44 lying upon the container head or wall 45. The flange 29 is formed by the inner edge portion of a flat ring 46 lying upon the flange 44, and rivets 47 pass through the parts 44, 45, 46, and 47 to secure them together.

60 In Fig. 6, the flange 30 is carried by a depressed portion 48 of the container head or wall 49, and the flange 29 is formed by an upwardly pressed portion 50 of a ring 51 which is secured upon the part 49 by rivets 52.

65 Excellent results are obtainable from the structures shown and they may therefore be followed. However, within the scope of the invention as claimed, numerous variations may be made. While a separate closure is shown in all views, the snap disk itself might well constitute the closure.

I claim:—

75 1. A container having an outwardly facing sealing ring seat, a sealing ring engaging said seat, a snap disk at the outer side of said sealing ring

for exerting an inward force to seat said sealing ring, a fulcrum rim fixedly carried by the container and disposed at the peripheral edge of said snap disk, and means releasable by turning of said snap disk for detachably connecting said snap disk with said rim, said turning being permitted by outward snapping of said snap-disk, said snap-disk having a portion for use in outwardly snapping it.

2. A container having an outwardly facing sealing ring seat, a sealing ring engaging said seat, a snap disk for exerting an inward force to seat said sealing ring, and a fixed fulcrum rim for the edge of said snap disk, said disk and rim having normally engaged lugs disengageable by turning of said disk, allowing removal of said disk, said turning being permitted by outward snapping of said snap-disk, said snap-disk having a portion for use in outwardly snapping it.

3. A container having an outwardly facing sealing ring seat, a sealing ring engaging said seat, a rim fixedly carried by the container and having inwardly projecting circumferentially spaced lugs spaced outwardly from the outer side of said sealing ring, and a snap disk for exerting an inward force to seat said sealing ring, said snap disk having fulcrum lugs lying against the inner sides of said rim lugs, said fulcrum lugs being engageable from said rim lugs by turning said snap disk, allowing removal of said snap disk, said turning being permitted by outward snapping of said snap-disk, said snap-disk having a portion for use in outwardly snapping it.

4. A container having an outwardly facing seat, a closure engaging said seat, a snap disk for holding said closure engaged with said seat, a fixed fulcrum rim for the edge of said snap disk, and means releasable by turning of said snap disk for detachably connecting said disk with said rim, said turning being permitted by outward snapping of said disk, said disk having a portion for use in outwardly snapping it, the diameter of said closure being less than the internal diameter of said rim, allowing removal of the closure when said snap disk is removed.

5. A container having an outwardly facing seat, a closure engaging said seat, a snap disk for holding said closure engaged with said seat, and a fulcrum rim for the edge of said snap disk, said rim and disk having normally engaged lugs disengageable by turning of said disk, said turning being permitted by outward snapping of said disk, said disk having a portion for use in outwardly snapping it, the diameter of said closure being less than the internal diameter of said rim, allowing removal of the closure when said snap disk is removed.

6. A container having an outwardly facing seat, a closure engaging said seat, a rim fixedly carried by the container and having inwardly projecting circumferentially spaced lugs spaced outwardly from the outer side of said closure, and a snap disk for exerting an inward force to seat said closure, said snap disk having fulcrum lugs lying against the inner sides of said rim lugs, said fulcrum lugs being disengageable from said rim lugs by turning said snap disk, said turning being permitted by outward snapping of said disk, said disk having a portion for use in outwardly snapping it, allowing removal of said snap disk, the diameter of said closure being less than the internal diameter of said rim allowing removal of said closure when said snap disk has been removed.

7. A container wall having an opening and a

- closure seated in and outwardly removable from said opening, a flat rim secured against the outer side of said wall around said opening, said rim having inwardly projecting circumferentially spaced lugs, and a snap disk for holding said closure against removal, said snap disk having fulcrum lugs lying against the inner sides of said rim lugs, said fulcrum lugs being disengageable from said rim lugs by turning said snap disk, said turning being permitted by outward snapping of said disk, said disk having a portion for use in outwardly snapping it, allowing removal of said snap disk and said closure.
8. A closure having an opening and rigid means around said opening providing an annular channel whose open side is disposed toward the axis of said opening, said channel having inner and outer side flanges, said outer flange having circumferentially spaced notches, a sealing ring within said channel lying against said inner flange, and a snap disk whose peripheral portion is received in said channel between said sealing ring and said outer flange, said snap disk having fulcrum lugs engaging the inner side of said outer flange and of a width to pass through said notches when said snap disk is sufficiently turned, said turning being permitted by outward snapping of said snap-disk, said snap-disk having a portion for use in outwardly snapping it.
9. A closure having an opening and rigid means around said opening providing an annular channel whose open side is disposed toward the axis of said opening, said channel having inner and outer side flanges, said outer flange having circumferentially spaced notches, a sealing ring within said channel lying against said inner flange, and a snap disk for holding said closure against removal, said snap disk having fulcrum lugs lying against the inner sides of said rim lugs, said fulcrum lugs being disengageable from said rim lugs by turning said snap disk, said turning being permitted by outward snapping of said disk, said disk having a portion for use in outwardly snapping it, the diameter of said closure being less than the internal diameter of said outer flange to allow removal of said closure after removal of said snap disk.
10. A substantially concavo-convex gasket-compressing lever-and-toggle-action snap-disk having short radial circumferentially spaced lugs to engage under corresponding lugs on a container when the disk is inserted, turned and snapped inwardly, said disk having a portion for use in snapping it outwardly to allow turning to released position.
11. A substantially concavo-convex gasket-compressing lever-and-toggle-action snap-disk having short radial circumferentially spaced lugs to engage under corresponding lugs on a container when the disk is inserted, turned and snapped inwardly, said disk having a portion sufficiently soft to permit puncturing thereof when the disk is to be outwardly snapped and turned to released position.

ROMAN B. BUKOLT.
